[57] CLAIM

The ornamental design for a roadside address sign with post, as shown and described.

DESCRIPTION

FIG. 1 is a front view of the roadside address sign with post of the present invention;

FIG. 2 is a rear view of the roadside address sign with post of FIG. 1.

FIG. 3 is a right side view of the roadside address sign with post of FIG. 1;

FIG. 4 is a left side view of the roadside address sign with post of FIG. 1;

FIG. 5 is a top view of the roadside address sign with post FIG. 1; and,

FIG. 6 is a bottom view of the roadside address sign with post of FIG. 1.

The broken lines are shown for illustrative purposes only and form no part of the claimed design.
